UNITED STATES PATENT OFFICE.

JOHN C. KINGSLAND, OF ARLINGTON, NEW JERSEY.

TRUSS.

1,240,732.

Specification of Letters Patent. Patented Sept. 18, 1917.

Application filed May 31, 1917. Serial No. 171,959.

To all whom it may concern:

Be it known that I, JOHN C. KINGSLAND, a citizen of the United States, residing at Arlington, in the county of Hudson and State of New Jersey, have invented certain new and useful Improvements in Trusses; and I do hereby declare the following to be a full, clear, and exact description of the invention, such as will enable others skilled 10 in the art to which it appertains to make and use the same.

This invention has for its object to provide a simple and efficient truss, which may be comfortably and effectively worn by the 15 user and which includes novel means for supporting the truss pads in position.

With this and other objects in view, the invention consists in the novel construction, combination and arrangement of parts as 20 will be hereinafter specifically described, claimed and illustrated in the accompanying drawing, in which:

Figure 1 represents a perspective view of the truss,

Fig. 2 represents a fragmentary rear elevation of one of the supporting plates of the truss,

Fig. 3 is a transverse sectional view of the plate,

Fig. 4 is a detail side elevation, partly in section of the truss pad, and

Fig. 5 represents a detail sectional view on the line 5—5 of Fig. 1.

Referring to the drawing in detail, the 35 numeral 5 indicates a pair of truss pads of oval shape and preferably constructed of rubber or other yieldable material, having an internal air-tight chamber to increase the resiliency of the pad. Screws 6 are adjustably fitted in internally threaded apertures formed in bushings or sleeves 16 fitted in the pads 5 and spring supporting rods 7 are looped about the shanks of the screws 6 and are suitably curved to comfortably fit the 45 body of the wearer.

The ends of the rods or wires 7 opposite the pads 5 are adjustably fitted in sleeves 8 rotatably mounted in apertures 7^a formed in lugs 9, carried by circular plates 10. The 50 plates 10 are preferably constructed of hard

rubber, or other non-corrosive material, and the front surfaces thereof, which engage the body of the wearer, are flat and smooth.

Metallic plates or straps 11 are secured to the plates 10 and are formed with longitudinal slots 12 pivotally receiving screws 13, which are threaded in the sleeves 8 and adjustably secure the terminals of the wires 7 in position therein.

The plates 10 are secured against movement longitudinally of the rods 7 by the screws 13, whereas the movement of the latter in the slots 12 permits a limited pivotal movement of the plates upon the rods so as to allow the plates to be adjusted in such 65 manner as to be comfortably worn by the wearer.

One end of a flexible strap 14 is secured under the headed terminal of one of the screws 13 and the other terminal of the 70 strap is provided with a plurality of apertures 15 to receive the other screw 13, whereby the plates 10 are adjustably connected.

One terminal of a connecting hook 17 is 75 looped and pivotally supported upon the screw 6 of one of the truss pads 5 and the opposite end of the hook is turned to provide a beak 18 for detachable engagement with the screw 6 carried by the other truss pad 5, thus forming a connection between 80 the front ends of the rods 7 for supporting the truss pads 5 in proper position with relation to the rupture.

What I claim is:

1. A truss comprising a pair of truss pads, 85 supporting rods, means pivotally securing the rods to the pads, a hook pivotally secured at the point of connection between one of the pads and rods and adapted to engage the other pivotal connection to connect 90 the pads, and adjustable means connecting the rear ends of the rods.

2. A truss comprising a pair of truss pads, a pair of rods connected with the pads, a hook pivotally secured to one pad and de- 95 tachably engaged with the other and providing a connection between the front ends of the rods, plates pivotally connected with the rear ends of the rods, and an adjustable connection between the plates.

3. A truss including a pair of truss pads, sleeves secured in the pads, screws fitted in the sleeves, supporting rods connected with the screws, means detachably connecting the screws, a pair of plates, sleeves pivotally and non-slidably mounted in said plates, and means adjustably securing said rods in said sleeves.

Copies of this patent may be obtained for five cents each, by addressing the "Commissioner of Patents, Washington, D. C."

In testimony whereof I affix my signature in presence of witnesses.

JOHN C. KINGSLAND.
